UNITED STATES PATENT OFFICE.

CHARLES M. MEAD, OF LOS ANGELES, CALIFORNIA, ASSIGNOR OF ONE-HALF TO MARK M. WORSTER, OF LOS ANGELES, CALIFORNIA.

DOUBLE-DECK WEB BED-AND-PLATEN PRINTING-PRESS.

1,121,745.

Specification of Letters Patent. Patented Dec. 22, 1914.

Application filed August 9, 1911. Serial No. 643,215.

To all whom it may concern:

Be it known that I, CHARLES M. MEAD, a citizen of the United States, residing at Los Angeles, in the county of Los Angeles and State of California, have invented a new and useful Double-Deck Web Bed-and-Platen Printing-Press, of which the following is a specification.

This invention relates more particularly to a job printing apparatus by means of which duplicate order books and the like can be simultaneously printed, perforated, numbered and assembled.

It also includes an attachment applicable for use with one or more job printing presses for the purpose of feeding a web to the press and of taking the web from the press, and delivering the printed sheets ready for issue, either as single sheets, consecutively numbered or otherwise; as letter heads, dodgers and the like; or as duplicate sheets, plain or consecutively numbered as the case requires; or as bill-heads and the like perforated and numbered in duplicate.

An object of this invention is to provide a novel unitary machine which will perforate in duplicate, number in duplicate, cut in duplicate and gather in duplicate sheets properly arranged as original and duplicate sheets ready for delivery to the stitcher and binder for making books or pads of bill-heads, sales-books and the like.

Other objects of the invention are simplicity, compactness and invariable appropriate performance of the necessary operations at the proper times.

Duplicate order books are usually made of a determined number of so-called original sheets interleaved with so-called duplicate sheets, the original sheets being consecutively numbered from unity beginning at the top original sheet and ending at the bottom original sheet, and the duplicate sheets being correspondingly numbered, one for and following each original sheet; the number of original sheets in each book varying according to convenience; and I shall illustrate the invention herein as adjusted for numbering books comprising fifty original and fifty duplicate sheets.

Another object is to provide for adjusting the numbering devices to the different sizes and forms of original and duplicate sheets, also to adjust the machine so as to number the leaves of some of the books and

to omit to number the leaves of others of the books being printed at one run, so that a single run of the press may produce one or more sets of numbered books, and one or more sets of unnumbered books; thus at one run, to supply various wants of different customers.

A further object is to provide means for issuing clean-cut sheets. This latter object is effected by providing means gripping the original and duplicate sheets while the same are being severed from the body sheets.

Other objects and advantages of this invention may appear from the subjoined detail description.

For convenience of description the terms original web and duplicate web will be used to designate the webs respectively for forming the original and duplicate sheets of the manifold.

Broadly considered the invention includes the combination with a platen printing press, of means for feeding a web to the press, and rotary means timed with the press to intermittently draw the web from the press.

It also includes the combination with the parts just enumerated, of means for feeding a second web to the web drawing means and mechanism timed with the web drawing means for cutting off the webs into sheets.

It also includes the combination with two platen printing presses of means for feeding webs to said platen printing presses, means timed with said presses to intermittently draw said webs from said presses, numbering mechanism timed with relation to the intermittent web drawing means and mechanism timed with said intermittent web drawing means to cut off sheets from the web.

Other objects, advantages and special features of invention may appear from the subjoined detail description.

The invention includes the combination with one or two platen presses, as may be required, of a double deck rotary web attachment; and it also includes said attachment and parts thereof. Said double deck rotary web attachment comprises a combination of mechanisms which may be enumerated as follows:—Mechanism X for drawing the webs; mechanism A, for adjusting the upper web relative to the cut-off; 110

mechanism B, for adjusting the lower web relative to the cut-off; mechanism C, for perforating the upper web; mechanism D, for perforating the lower web; mechanism 5 E, for numbering the upper web; mechanism F, for numbering the lower web; mechanism G, for shifting the upper inking ribbon to coöperate with the upper numbering mechanism; mechanism H, for shifting 10 the lower inking ribbon to coöperate with the lower numbering mechanism; mechanism I, for cutting the printed and numbered duplicate sheets from the webs; mechanism J, for gripping the webs during the 15 cutting operation; mechanism K, for resiliently holding the webs by the drawing rollers; mechanism L, for regulating the length of web delivered to the cut-off means thus to regulate the length of the delivered 20 sheets; mechanism M, for delivering the cut-off sheets in a stack.

The invention also includes the combinations constituting such mechanisms, and various parts and combinations of parts more 25 particularly set forth in the appended detail description and claims.

The accompanying drawings illustrate the invention.

Figure 1^a is a diagrammatic view of a 30 combination involved in this invention. Various parts, including the mechanisms G, H, K and M, are not indicated in this view. Fig. 1 is a fragmental perspective view taken from the operator's side of the apparatus and particularly showing the novel double deck rotary web attachment for job printing which forms a part of this invention. An original web is shown as coming from a printing press (not shown in this 35 view) and a duplicate web is shown as feeding from a roll. Fig. 2 is a fragmental perspective view showing said attachment from the side opposite that shown in Fig. 1. Fig. 3 is an enlarged broken fragmental detail viewed from line x³, Fig. 4, and showing the mechanisms A and B for adjusting the cut-off, and the mechanisms C and D for perforating the upper and lower webs. Fig. 3^a is an enlarged fragmental detail partly in 40 section of a perforating roller and one of the perforating wheels therefor. Fig. 4 is a broken elevation in section on line x⁴, Fig. 3. Fig. 5 is an enlarged cross sectional detail on line x⁵, Fig. 4, looking in the direction of the arrows. Fig. 6 is a fragmental 45 broken elevation from the operator's side, partly in section and viewed in part from line x⁶, Fig. 7, and illustrating the mechanisms E, F, G and H. Broken lines indicate the actuating parts of the numbering 50 mechanisms E and F in operative position. Fig. 7 is a fragmental broken transverse section viewed in part from x⁷, Fig. 6, looking in the direction of the arrows. Parts 55 are sectioned at other planes, the indication 60

of which on other views is not attempted. Fig. 8 is an enlarged fragmental detail of one of the lower numbering units and the actuating parts therefor. Solid lines show parts in the operating position while broken lines illustrate the normal position, corresponding to the position shown in solid lines in Fig. 6. Fig. 9 is an enlarged fragmental broken plan detail viewed from line x⁹, Figs. 6, 7 and 10 to illustrate the inking 65 ribbon shifting mechanism H. Parts are broken away for clearness of illustration and also to contract the view. Fig. 10 is an enlarged fragmental broken elevation of parts shown in plan in Fig. 9. Solid lines illustrate the position of parts at a step in the shifting operation, while broken lines indicate the normal stationary position shown in solid lines in Fig. 6. Parts are broken away for clearness of illustration. Fig. 11 is a fragmental broken mid-sectional elevation on line x¹¹, Fig. 12, illustrating the mechanisms I, J and M. Broken lines show the position of the actuating parts of the cutting and gripping mechanisms I and 70 J at the close of the cutting stroke; while solid lines show all parts in the normal position. Fig. 12 is a broken front sectional elevation view from irregular line x¹²—x¹², Fig. 11. Parts are in the position shown in solid lines in Fig. 11. Fig. 13 is an enlarged fragmental front detail of the cutting and gripping mechanisms viewed from irregular line x¹²—x¹³, Fig. 11 and line x¹³, Fig. 15. The cutter is shown in dotted lines at the 75 completion of one-half of the cutting stroke. Fig. 14 is a broken plan of the parts shown in Fig. 13 and viewed from line x¹⁴, Figs. 13 and 15. Dotted lines indicate the position of the cutter at the completion of the cutting stroke. Fig. 15 is a fragmental sectional detail on line x¹⁵, Figs. 13 and 14 showing the cutting and gripping mechanisms in the normal positions corresponding to those shown by solid lines in Figs. 11 and 80 13. Fig. 16 is a view analogous to Fig. 15 showing the cutter at the completion of one-half of the cutting stroke and the gripping mechanism in gripping position. Fig. 17 is an enlarged detail elevation partly in section on line x¹⁷, Figs. 12, 13 and 14, showing the cutter and means for mounting the same. Fig. 17^a is a full size fragmental sectional detail illustrating the means for adjusting the cutter. Fig. 17^b is a view taken 85 from line x^{17b}, Fig. 17^a and looking in the direction of the arrows. Fig. 18 is a fragmental broken plan of the mechanisms K and L viewed from line x¹⁸, Fig. 19. Parts are broken away to expose parts that would 90 otherwise be hidden. Fig. 19 is a fragmental side elevation of the parts shown in Fig. 18 as they return to the beginning of a feed stroke. The position of parts at the beginning of a feed stroke is indicated in broken 95 100 105 110 115 120 125 130

lines and the position at the completion of said stroke is indicated in dotted lines. Fig. 20 is a diagrammatic elevation of the webs shown in Fig. 19, and the rollers around which they run. Fig. 21 is an enlarged detail in section on line x^{21} , Fig. 19. Fig. 22 is an enlarged cross section on line x^{22} , Fig. 19. Fig. 23 is a view on reduced scale of a full sheet and fragments of two other sheets 10 of the finished product, parts of the original fragmentary sheets being broken away to expose the duplicates beneath. Fig. 24 is a diagrammatic view of the apparatus comprising two printing presses and the attachment combined. Dotted lines indicate an alternative position of one of the presses. Fig. 25 is a diagram illustrating the travel of the original and duplicate webs when the attachment is combined with only one press 15 for printing only the original sheets the duplicate sheets being left blank.

The invention may be applied as a unitary machine having a single unitary frame of any desirable form, which carries two 20 platen presses and the apparatus which I call the attachment, all arranged in fixed relation to each other on the one frame. For convenience in supplying the invention at minimum cost to printing establishments 25 already supplied with one or more platen printing presses the apparatus herein termed the attachment may be constructed independently of a specially manufactured frame for the printing presses; and where it is desired to mount both platen 30 presses and the attachment on a common floor Y, said attachment will be placed between the printing presses as indicated in Fig. 24, and said floor will serve as a common 35 frame for both presses and the attachment.

In the drawings 1 and 2 represent webs fed from rolls 3, 4, which may be situated on opposite sides or both on one side only 40 of the attachment. These webs when run through the attachment are finally brought together with those sides uppermost which are to receive the numbers, the duplicate being underneath the original.

5, 6 designate the two platen presses between which may be located the attachment through which, in the complete apparatus, the two webs are run on their way from the platen presses to the tray on which the 55 completed sheets are finally laid.

Where both original and duplicate sheets are to be printed the web 1 is led from the roll 3 to the press 5 and from such press over suitable guide-rollers to the upper 60 part of the attachment; and the web 2 is led from the roll 4 through the platen press 6 over the guide-roller 7 into the attachment underneath the original web as diagrammed in Fig. 24. Where the attachment 65 is between the presses, and only the original

is to be printed and the duplicate is to be unprinted, the web 2 is used as the original; being led through the press over the guide-roller 7 on to the upper part of the attachment, while the web 1 is led from the roll 70 3 directly to the lower part of the attachment as shown in Fig. 25, without being passed through a press.

In Fig. 24 the web 1 is led up from the press over the guide-rollers 3", 8 and 9 75 which are above the mechanisms of the attachment, and thence down to the top-web adjusting roller 10, thence over the perforating roller 11, thence underneath the rider roller 12, thence around the pair of pulling 80 rollers 13, 14 and thence out between the delivery pulling rollers 14 and 15. The duplicate web is led from the press 6 over the lower guide-roller 7; and thence under the lower web adjusting roller 10"; thence 85 over the duplicate perforating roller 11"; and thence under the lower pulling roller 16 and around said roller and between it and the delivery pulling roller 15 and thence out between the delivery pulling rollers 14 90 and 15 and beneath the web 1.

Where it is desired to print only the original, the web 2 is used for the original and is passed through the press 6 over the guide-roller 7 under the lower web adjusting roller 10"; thence over the perforating roller 11 and thence to the pulling roller of the web drawing mechanism X, as above described, while the web 1 is led directly from the roll around the guide rollers 18, 19, 20; 100 thence over the perforating roller 11", and thence under the lower pulling rollers 16 and 15 and out from between the rollers 15 and 14 toward the cutting mechanism I.

The numbering devices 21 and 22 for the 105 two webs are arranged between the perforating rollers 11, 11" and the pulling rollers of the web drawing mechanism X.

It is thus seen that a feature of this attachment is the arrangement of web drawing mechanism at one end and web adjusting mechanism at the other end of the attachment and mechanism for operating on the web, as the perforators and numbering devices, between the adjustable web adjusting rollers and the web drawing rollers; and said web-drawing mechanism and numbering devices work intermittently and alternately to one another.

The presses 5 and 6 may be reversely fed 120 as in Fig. 24 so that the printing effected by one is on the under side and that effected by the other is on the upper side of the webs, respectively, at the presses and numbering is done on the upper side of 125 both webs at the numbering devices.

In the arrangement shown in solid lines in Fig. 24 the webs are reversely arranged and the presses are set with the type facing away from the attachment; and when both 130

webs are to be printed, the web 1 enters the press 5 at the bottom and leaves it at the top so that when the web has passed over the carriers 8 and 9 and under the web adjusting roller 10, the printing comes to the upper side and is up as the web passes over the perforator roller. The web 2 enters its press 6 at the top and leaves such press from the bottom, and consequently the 10 printing is at all times on the upper side of the web 2.

Ordinarily where an attachment has been installed and only one press is to be used, the arrangement will be such as is shown in 15 Fig. 25, the web 2 being taken from the roll directly to and over the guide-roller 7 and under the lower web adjusting roller 10" and the web 1 will be carried as directly as possible to the perforating roller 20 11". In this way the long pull on the web that is apparent in Fig. 24 between the press 5 and the adjustable roller is avoided, but by providing the guide rollers 3" 8, 9 the use of two old presses with a new attachment 25 is made easy and by providing the guide rollers 18, 19 and 20 the pull on the unprinted web is shortened. However, when the two platen presses and the attachment are in the relative positions shown in Fig. 30 1^a the web 1 remains as the original web and may be printed by the press 5 while the press 6 is standing still; being thrown out of gear by a clutch, not shown.

Where the original and duplicate webs are 35 to be printed as indicated in Figs. 1^a and 24, it is necessary that the printed portions coming from the two printing presses must exactly register with each other and in order to secure such registration it is necessary 40 that the length of the web between the delivery web drawing rollers 14 and 15 and each of the presses shall be in each instance some exact multiple of the size of the printing forms of the press and it is also necessary 45 that the cut-off shall operate in due relation to the delivery rollers 14 and 15 as they deliver the printed sheet.

The frame 23 of the attachment when made as a separate part of the machine is of 50 any desired construction, preferably of angle-iron or channel-iron, these different materials being used in accordance with the best methods of the structural art within the judgment of the builder.

55 *Mechanism "A" for adjusting the upper web.*—Referring now to Figs. 3 and 4, the upper web adjusting or take-up roller 10 is carried by an adjustable head 24 fixed by bolts 25 to connections that are preferably 60 sprocket chains 26 which pass around the upper and lower pulleys that are preferably sprocket wheels 27, 28 arranged in pairs. The upper sprocket wheels 27 are fixed by set screws 29 to a shaft 30 which is journaled 65 in boxes 31 on the frame 23 and secured

against shifting by means of collars 32 and provided with a handle 33. The lower pulleys 28 are mounted on a common axis 34 journaled in the arms 35 and secured against shifting by collars 36. Said arms 70 35 are pivoted by pivot bolts 37 to the frames 23 and are adjustably held by tension bolts 38 by means of which the arms 35 may be drawn down in order to hold the endless connections 26 taut. The upper web adjusting roller 10 is adjustably secured to the head 24 by bolts 39 that are held between the head 24 and the head bar 40 and that pass through slots 41 in journal hangers 42 in which the journal pins 43 of the roller 80 10 are carried. The bolts 39 are held between the head 24 and the head bar 40. Said head bar is held to the head 24 by the bolts 44 passing through the spacers 45 located between the head 24 and the head bar 85 40. Said head and head bar are mounted between the vertical guides 46, 47 arranged in pairs on opposite sides of the machine and which form the vertical ways 48 for the ends of the head and head bar. Space blocks 90 49 are held by the bolts 44 to contact with the guides 46, 47 to prevent endwise movement of the head and consequently of the roller. The handle 33 affords means to move the connection to move the head and the adjusting roller up and down.

The mechanism B for adjusting the lower web relative to the cut-off and other mechanisms that operate on the printed web below the levels of the supporting rollers 9 and 11 100 thus to increase the distance the web travels between the press and the cut-off and other mechanisms that operate on the printed web is practically the same as that just described and in the drawings the parts of the mechanism B which correspond to parts of the mechanism A are indicated by corresponding characters with the addition of indices.

110 *Mechanism C for perforating the upper web.*—The perforating wheel 50 is a finely-toothed sharp-edged wheel journaled by the stud 51 on the arm 52 fixed to a shaft 53 that is journaled in clamping boxes 54 on the frame 23 and provided with a handle 55. The 115 clamping boxes 54 are blocks provided near one end with a bore 56 to receive the shaft 53 and being split at 57 to form arms 58, 59 which are transversely bored to receive a bolt 60 which passes through a flange α of 120 an angle-iron forming part of the frame 23, said bolt 60 being provided with a thumb-nut 61, so that the arms 58, 59 can readily be drawn together so as to hold the shaft 53 with any desired degree of friction, by 125 this means to adjust the perforating wheel 50 into and out of coöperative relation with the perforating roller 11 as shown in Figs. 3 and 1, respectively. The perforating roller 11 is provided at intervals of about 130

1 of an inch, more or less, with grooves 62 into which the sharp tooth edges 63 of the perforator wheel 50 may run. The gudgeons 64 of the perforating roller 11 are carried in notches 65 of brackets 66 fixed to the frame 23 and when the perforators 50 are thrown out of commission as seen in Fig. 1 the perforating rollers may be lifted out and replaced as described.

10 The perforating wheel can be adjusted to any suitable positions upon the shaft 53 and may be securely fixed thereto by set screws. The perforating wheel may be raised and lowered out of and into commission as desired by means of the handle 55. Any desired number of perforating wheels may be applied on the shaft 53.

15 The mechanism "D" for perforating the lower web corresponds to that just described and parts corresponding to those of mechanism "C" are indicated by corresponding characters with the addition of an index.

20 Separate numbering mechanism is employed for intermittently numbering the webs respectively between the presses and the web drawing mechanism. The numbering mechanisms are operatively connected with and are timed with the platen presses.

25 *Mechanism "E" for numbering the upper web.*—The mechanism for numbering the web (see Figs. 6, 7, 8) comprises a bed 67 under the web, an automatic numbering machine 68 and intermittent mechanism connected with the operating parts of the apparatus to intermittently operate the numbering machine in synchronism with the platen of the press. Any desired number of the machines 68 may be employed, there being as many automatic numbering machines as 30 there are bill heads or other printed articles contained in one impression of the form.

35 The automatic numbering mechanism is provided with a cross-head formed of bars 69, 70, spaced apart by washers 70" and fastened to each other by bolts 71 and being in parallelism with the web-carrying rollers, and forming tracks for the numbering machine carriages comprising opposite sides of said bars 69, 70, and adjustably clamped 40 upon said bars by bolts 72 having thumb nuts 73 provided for that purpose.

45 The stems *b* of the numbering machines are fixed by pins *c* to axles *d* which are journaled in the blocks *a* and against which axles the type and ink-pad retracting springs *e* impinge to normally hold the guide feet *f* depressed toward the web and allowing the stems *b* to move down relative to the feet when said feet impinge upon the web; 50 and thus allowing the type to be forced down onto the inking ribbon above the web.

55 By means of the axles the numbering machines are gravity-adjusted to properly act on the inking ribbon above the web.

60 65 By constructing the cross-heads and car-

riages as shown, one or more numbering machines may be mounted on each cross-head and can be shifted therealong transversely of the web so as to provide for numbering the web at whatever point required. Each 70 numbering machine is independently movable. Said cross-heads are provided with perforated end plates 74, 75, through which vertical actuating rods 76 play, said rods being provided with adjusting collars 77 75 held by set-screws 78 to support the lower end plates 75. Depressing springs 79 are fixed on the rods 76 by adjusting collars 80 which compress the springs 79, thus yieldingly holding the cross-head down firmly 80 upon the supporting collar 77. Longitudinal clamps formed of bars 81, 82, held toward each other at their ends by bolts *g* are provided to mount the slidable rod guides 83 and also to support transverse shafts. 85

The rod guides 83 are slidable on and adjustably fixed to the guide bars 81, 82, by means of clamp bolts *h* that pass between said guide bars and are tightened therein by nuts *i*. Boxes *j* having studs *k* that also 90 pass between and are clamped by guide bars 81, 82, are provided to support ribbon roller shafts hereinafter described.

Several sets of upper and lower numbering mechanisms may be provided for the apparatus. In Fig. 6 two such sets are shown. The upper and lower cross-heads of each set are connected together by the vertical actuating rods 76 that work through the guides 83, and that are provided with extension joints 95 84 pivoted at 85 to the rods 76 and pivoted at 86 to U-shaped sliding clamps 87 that are fixed by bolts 88 that pass through the limbs of the clamp and are secured by the wing nuts 89. Said clamps 87 are adjustably 100 clamped on the cam levers 90 provided with the riders formed of rollers 91 that rest upon the peripheries of the cam wheels 92. The rollers 91 are mounted in pairs upon shafts 93, 93' and the cam wheels 92 are 110 mounted in pairs upon the secondary shaft 94 and the main shaft 94'. 110

The means for numbering the lower web correspond to those just described and are marked in the drawings with like characters 115 distinguished by indices.

In Figs. 6 and 7 like parts are designated by like characters, indices being applied to such characters to distinguish the parts variously located. The secondary shaft 94 120 shown in Figs. 6 and 7 is driven by the main shaft 94' through sprocket gears 95 and chain 96. The parts more directly relating to the main shaft 94' are distinguished by indices. The shafts 94 and 94' are journaled in boxes 97 fixed to the frame 23 and the sprocket wheel 95' and the cam wheels 92' are fixed on the main shaft 94' which is driven by the large sprocket wheel 98 driven by the sprocket chain 99 driven by the speed- 130

increasing gear 100. The peripheries of the cams 92 and 92' are mainly circular, being provided with recesses 101, 101' adjoining the circular portions 102, 102' that are curved so as to allow the riders 91, 91' to descend and rise with a smooth motion. The levers 90 and 90' are respectively fulcrumed at 103 to the frame 23 at the ends opposite the rods 84. The riders 91 rest upon the peripheries of the cams 92, 92' and support the weights of the levers 90 and 90' and the numbering mechanisms carried thereby respectively, so that at each revolution of the cams 92, 92' the rods 84 are vertically reciprocated. On the main shaft 94' is also fixed the knife-operating cam 104 which carries the wiper wheel 105 the stub axle 106 of which is fixed to the knife-operating cam 104. As the levers 90 and 90' move up and down they vertically operate the cross-heads and the numbering machines carried thereby.

Mechanism "G" and "H" for shifting the inking ribbon.—The inking ribbon shifting lever 107 is fulcrumed to the frame 23 by the fulcrum pin 108 and is arranged above the wiper wheel 105 and is pivotally connected by the pin 109 with the vertical connecting rod 110 which is guided by the guide 112 that is fixed to the frame 23. Said connecting rod 110 is pivotally connected by means of pins 113, 113' with the slotted pawl-levers 114, 114' which are fulcrumed on the axes 115, 115' of the ribbon rollers 116, 116', there being ratchet wheels 117, 117' fixed to the axes 115, 115' and operated by the pawls 118, 118' that are pivoted to the pawl levers. It is thus seen that at each revolution of the knife operating cam 104 the ribbon roller will be rotated a distance, thus shifting the inking ribbon 119, 119'. Sets of ribbon-shifting rollers that are practically alike are reversely arranged on opposite sides of the connecting rod 110, so that when the pawls 118 on one side of the connecting rod are in engagement, the ribbon will be shifted in one direction and when the pawls 118' on the other side of the connecting rod are in engagement with the ratchet wheels the ribbon will be shifted in the other direction, care being taken that only the pawls on one side will be thrown in at the same time. The ribbon passes from one ribbon roller 116 to the other ribbon roller 116' under depression rollers 120 which extend across the machine and are located just above the paths of the webs 1 and 2.

Mechanism "I" for cutting the printed and numbered duplicate sheets from the web.—At each revolution the knife-operating cam 104 (see Figs. 1 and 19) depresses the roller 121 which is mounted on the cutter lever 122 that is fixed by bolts 123 to a box 124 having a hub 125 which is fixed by a pin 126 to the cutter shaft 127 journaled

in a stationary box 128 that is fixed on one side of the frame 23. The cutter shaft 127 carries the cutter arm 129 fixed thereto, and to the end of which is pivoted by a pin 130 the knife-operating connecting rod 131 that is pivoted at its upper end by pivot 132 (see Fig. 13) to the cutter knife 133 which is pivoted by the pin 134 to the lower stationary blade 135 of the cutter. A spring 136 (see Fig. 1) is connected at its lower end to the cutter lever 122 between the box 124 and the roller 121 at its upper end to a bracket 137 that is fixed to the frame 23. The purpose of this spring is to hold the cam roller 121 against the cam 104. The cutter shaft 127 extends across the frame 23 and through a box 138 and is provided with an arm 139 to which the cutter arm retracting spring 140 is connected to assist the spring 136 to lift the cutter knife 133. By means of the springs 136 and 140 the cutter lever 122 the cutter arm 129 connecting rod 131 and the free end of the knife 133 are normally raised to admit the web between the knife and the lower cutter blade 135.

It is necessary that the paper be held firmly on both sides of the knife during the operation of cutting and also that the web shall be stripped from the knife as the knife rises. The delivery rollers 14, 15 hold the webs on one side of the cutter, and the movable gripper jaw 141, in connection with the stationary gripping jaw 141', intermittently hold the webs on the delivery side of the cutter.

The stripper 142 loosely rides on the top of the knife, and is provided at its ends with sleeves 143 that slide up and down on the gripper operating rods 144 to which the gripper jaw 141 is fixed, and which rods slide up and down in guides 145. Said rods are mounted at their lower ends on a cross bar 146 (see Figs. 11, 12,) which is fixed by nuts and bolts 147 to a central gripper lever 148 that is journaled by the box 149 on a shaft 150 that is journaled in boxes 151 on the frame 23. The lever 148 is provided at its sides with rollers 152, 152' which are operated in succession by the intermittent cams 153, 154 that are adjustably fixed by set screws 155 to the main shaft 94'. The gripper lever 148 is yieldingly held down by the spring 156 and is lifted in opposition to said spring by the intermittent cams 153, 154 which are arranged in such operative relation to the other parts of the machine, that, just preceding the descent of the knife 133 they will allow the spring 156 to bring the gripping jaw 141 to gripping position. The intermittent cutter operating cams 153, 154 have carrying arcs 157, 158 of more than 180° concentric with the main shaft 94'. The cam wheels are spirally arranged relative to each other on the shaft to leave a recess 159 between their carrying arcs 157,

158 so that during the greater portion of the revolution of the main shaft 94' the cams will support the lever 148 to uphold the gripping jaw 141, but during a less portion 5 of such revolution will allow the lever 148 to descend. The recesses 159 of the cams are on one side of the shaft to allow the rollers 152, 152' to be simultaneously fully depressed for an instant so that the gripping jaw 141 may be momentarily forced by spring 156 to grip the webs.

The rollers 152 and 152' are arranged on diametrically opposite sides of the main shaft 94' and the tip of the cam 104 is arranged diametrically opposite the combined recess 159, so that the cutting stroke of the knife is effected at the instant the gripping stroke of the gripper is effected. In this way the web is firmly held by the gripper 15 at the instant the sheet is cut off and is then released. The cam 104 forms on one side of the shaft an arc concentric with the shaft and on the other side of the shaft, with a cusp of much greater radius so that both the 20 knife and the gripper bar are normally raised.

By means of the set screws 155 the cutter-operating cams may be adjusted to reduce or increase the width of the recess, thus to increase or decrease the length of the gripping 30 and cutting stroke.

In order to prevent the knife from lifting the severed ends of the web as the knife returns upward the stripper 142 is vertically movable relative to the knife, there being for this purpose slotted fingers 160 adjustably fixed to the stripper by bolts and nuts 161 and underneath the web the receiving bed 162 is arranged immediately below the 35 stripper so that when the knife descends the stripper will rest on the webs and hold them tightly on the receiving bed while the knife is making and withdrawing from its cutting stroke. That is to say, the stripper will 40 come into contact with the web immediately before the knife begins cutting the web and will rest on the web throughout the remainder of the descending stroke and a part of the return stroke of the knife; being held 45 in place by the sleeves 143 on the rods 144.

Referring now to Fig. 13, broken lines indicate positions of the knife and stripper on the cutting stroke. These positions are clearly seen in Fig. 16. When the knife 50 ascends the stripper lags behind until the knife is fully withdrawn from the stationary cutter blade 135; whereupon the knife again lifts the stripper. In order that the cutting knife may be comparatively light and will 55 make a close cutting engagement with the stationary cutting blade means are provided for holding the knife tilted transversely away from the stationary blade and sprung longitudinally toward the stationary blade; 60 and the stationary blade is aslant trans-

versely toward the cutting knife. This will be understood by reference to Figs. 14, 15, 16, 17, 17^a and 17^b. The knife is loosely fulcrumed on the pin 134 and fulcrumed in hole 163, the fulcrum pin 134 being of less 70 diameter than the hole 163 through which the pin extends, said pin being screwed into the stationary blade 135 and into the frame 23. An adjustable shim 164 provided with a slot 165 is fastened to the contact side of the 75 knife by set screw 166. Said shim is bifurcated at its lower edge and is slidable up and down relative to the fulcrum pin 134 between the furcations of the shim. The shim is wedge shape diminishing downwardly, and by shifting it down or up relative to the knife it will tilt the knife at a greater or less angle relative to the stationary blade. At the free end of the knife a swinging arm 167 is hung from a stud 168 80 on which it is secured by collar 169 and the arm is in sliding contact with a finger 170 that projects from the free end of the knife. The swinging arm is resiliently held by a spring 171 against the finger 170, thereby 85 springing the knife toward the stationary cutter blade 135. The knife spring 171 is held in place by a guide bolt 172 passed through and loosely held at one end by the lower end of the swinging arm 167, and held 90 at the other end by the bracket 173 riveted to the frame 23. The lower stationary blade 135 is fixed to the frame 23 by bolts 174 and is held atilt by the shim 175 that is interposed between the blade and the frame. 100 By this tilted arrangement of the blades, the cutting edges are always in cutting relation to each other so that when the knife is moved down it will invariably cut the web smoothly and the blades have a self-sharpening tendency when operated. The stationary gripper jaw 141' is tightly fixed on the bolts 176 that are fixed to the frame 23; and is provided on its upper edge with a rubber gripping strip 177 to coöperate with a like 105 strip 178 on the upper gripping jaw 141 so as to cushion the gripping stroke and to insure a tight grip on the webs between said strips.

Mechanism "K" for resiliently holding the web.—The upper delivery pulling roller 14 is stationarily mounted being journaled in the bars 179 that are fixed to the frame 23 by bolts 180, and the lower side of the roller is just above the level of 120 the receiving bed 162 so that practically the web coming from the under side of the roller will pass horizontally to the bed. (See Figs. 19, 11, 12 and 15.)

The upper pulling roller 13 is mounted 125 on a lever 181 that is fulcrumed by bolt 182 to the frame 23 and is connected with tension spring 183 to force the upper pulling roller down upon the upper delivery roller, thus gripping the web between the two. 130

The lower delivery pulling roller 15 is mounted on a lever 184 fulcrumed to the frame at 185 and pressed upward by the spring 186 carried by the rod 187 and hanger 188 which is fixed to the frame 23 and the lower pulling roller 16 is mounted on a lever 189 fulcrumed at 190 on the frame 23 and pressed upward by the spring 191 mounted on a rod 192 which is fixed to the frame 23. By this means the web is gripped and fed in true position to the receiving bed 162.

It is important in the operation of this machine including two printing presses by which both originals and duplicates are simultaneously printed that the webs shall be pulled or fed with exactness, so that they will perfectly register. Otherwise the webs may creep with relation to one another and a slight creeping would mar or spoil the completed job. This fact has proved in many experiments to offer a very great difficulty and to overcome this the pulling rollers are provided with a facing 193 of sand paper or its equivalent.

A satisfactory facing is made of the sand paper known to the trade as No. 2 garnet, said paper being coarse, rough surfaced, very light and not liable to wear out or become smooth.

In case the facing becomes smooth it may be renewed by replacing with new, the paper being cut to the exact circumference of the roller and its edges being fastened to the roller by small tacks as indicated at 194 in Fig. 12.

Mechanism "L" for regulating the length of the web delivered to the cut-off.—It is necessary in a machine of this character that the delivery sheets shall be cut off in certain lengths and that the line in which they are cut off shall exactly register with the division between the printed forms on the webs. For this purpose the pulling roller driving arm 195 is fixed to and revolves with the main shaft 94'. To this arm 195 is adjustably fixed the crank-pin 196 adapted to fit in any one of the series of holes 197 that are at different radial distances from the main shaft 94'. To this crank-pin is connected a pitman 198 which is connected by a wrist-pin 199 to an adjustable clamp composed of two clamp-plates 200, 201, which are placed face to face and are provided with recesses 202 in which a pulling extension arm 203 may slide; and upon said arm the clamp-plates may be tightly clamped by means of the clamping bolts 204, 205, the former of which pass through a spacer 206 that is in contact with the arm 203. The clamp bolts 205 are arranged on the opposite side of the recesses 202 and arm 203 from the spacer 206 for the purpose of springing the clamping plates 200, 201, to tightly clamp the pull-

ing arm 203. By loosening the bolts 205 the clamp plates and spacer may slide on the pulling arm 203 radially toward and from the axis 207 of the pulling spur wheel 208 which is rotated by engagement of the detent 209 with the teeth 208' of the spur wheel; said detent being carried pivotally by the pin 210 on the pulling lever 211 that is journaled by the boxes 211' on the axis 207 of the pulling wheel 208. The spring 212 holds the detent in engagement with the spur wheel 208.

A pair of back stop pawls 213 are mounted on elongated stems 214 that are pivotally mounted on the frame 23 by a stud shaft 215. The tips of said pawls have beveled edges 216 engaging in beveled peripheral grooves 217 in the rim of the spur wheel on opposite sides of the teeth 208' thereof. Weights 218 are suspended by wires or chains 219 to the stems 214 to hold the back stop pawls in frictional engagement with the grooves on the rim of the wheel 208 behind the detent 209. The purpose of the pawls 213 is to prevent retraction of the pulling wheel 208, the teeth 208' of which mesh with pulling roller main gear 220 fixed to the shaft 14" of the delivery pulling roller 14. The teeth 208' are fine and the diameter of the wheel is large so as to minimize variation in the cut off. The pulling rollers are provided with gears 223, 224, 225 and 226, respectively which are in a train that gives the proper directions to the several pulling rollers 13, 14, 15 and 16.

In practical operation the crank arm 195 revolves as the shaft 94' rotates and this reciprocates the pitman 198 and swings the pawl 209 to rotate the wheel 208. The length of stroke of the pawl can be roughly adjusted by changing the pin 196 to the appropriate one of the holes 197. The fine adjustment of the stroke is then made by shifting the clamp forming the plates 200, 201 along the pawl arm extension 203 to increase or decrease the radius of the wrist-pin stroke. In this way the length of the web which is drawn forward at each revolution of the main shaft may be minutely determined and accurately gaged, so that each sheet will be of the appropriate length.

Mechanism "M" for delivering the cut-off sheets in stack.—The fly-operating lever 227 is fulcrumed at one end to the frame 23 at 228 and is provided intermediate its ends 120 with a cam roller 229. A connecting rod 230 is pivoted to the other end of the fly-operating lever 227 and is connected with a crank-pin 231 adjustably mounted on the mutilated gear wheel 232 the teeth of which mesh with pinion 233 fixed to the shaft 234 of the fly 235. A retracting spring 236 fastened to the frame at one end and to the crank arm 237

at the other end acts through the gears 232, 233 and shaft 234 to normally draw the fingers of the fly 235 into the sheet receiving position shown in Fig. 11. A cam 238 adjustably mounted on and rotating with the main shaft 94' is provided opposite the pulley roller driving arm 195 and is arranged with an arc 239 nearly opposite the pulley roller driving arm so as to come into contact with the cam roller 229 and move the lever 227 down so as to operate the fly 235 on the back stroke of the arm 195, thus operating the fly to take the cut-off sheet and deliver it in the tray 240 while the web is resting. The arc 239 is about a quadrant so that the operation of the fly occurs only during about one-quarter of the revolution of the main shaft. The fly-operating cam 238 is adjustably fixed to the shaft 94' by a set screw 241 and can be turned relative to the shaft 94' and the arm 195 so as to operate the fly 235 at the appropriate time.

In Figs. 1 and 2, 242 indicates the usual paper guiding fingers which are shown mounted on the slotted arms 243 that are secured by thumb nuts 244 to the receiving tray 240, thus to keep the paper straight on the tray. A brake lever 245 is connected by a shaft 246 with a crank arm 247 and connecting rod 248, lever 249 and link 250, with a brake shoe 251 that is adapted to engage the fly wheel 252 of one of the platen printing presses. Said printing presses are connected in timed relation with each other by the train 253, and said presses are connected by sprocket wheel 254 and sprocket chain 255 with sprocket wheel 100 and shaft 256 on which the sprocket wheel 100 is mounted, and which is also provided with sprocket wheel 257 to drive the sprocket chain 99. A web roll brake indicated at 258 is provided to prevent the web from racing.

In Fig. 1^a two power belts 259, 259' are indicated for driving the presses 5 and 6 and two sprocket chains 255 and 255' are shown, one connecting the press 5 and the other the press 6 with a sprocket wheel 100 of the attachment, it being understood that a sprocket wheel be provided for each of the sprocket chains and that either chain may be thrown out of gear by clutches, the handles 260 of which are shown and that one of the gears in the train 253 may be removed and the sprocket wheel 100 driven by the sprocket chain 255' may be thrown out of action when it is desired to pass the duplicate web 2 through the attachment unprinted.

In practical use it is understood that the method of connecting the presses with the mechanism of the attachment may be varied within the judgment of the constructor, so that either or both of the presses may be run as desired.

In Fig. 23 there are shown one complete

and two fragmentary sheets cut from the webs. The original and duplicate sheets 500 and 501 are printed to form the leaves of order books, there being four of such leaves to each sheet.

The practical operation of the machine will be understood from the foregoing.

To print the sheets for a book containing printed original and duplicate sheets the webs 1 and 2 from the rolls 3 and 4 will be carried through the printing presses and through the attachment to the pulling rollers as indicated either in Fig. 1^a or Fig. 24 and then upon applying power to drive the mechanism the two presses and their mechanism will operate to produce and deliver the printed sheets onto the tray 240.

When it is desired with the arrangement shown in Fig. 24 to omit the printing from the duplicate sheet the webs will be led through the attachment in the manner suggested by Fig. 25.

I claim:—

1. The combination with a plurality of printing presses, of means to supply webs to the presses, intermittent means timed with the presses to draw the webs from the presses, intermittent mechanisms to simultaneously operate on the printed webs, and adjusting mechanisms between the presses and the web-drawing means to regulate the webs relative to one another to bring the printed matter on one web into registration with the printed matter on the other web.

2. The combination with web printing and web drawing mechanisms of web guide rollers, an adjustable head, endless connections to which the head is fixed, pairs of upper and lower pulleys around which said connections pass, a shaft to which one pair of pulleys is fixed, means to hold the lower pulleys to keep the connections taut, a web adjusting roller secured to the head, and means to move a pair of the pulleys thus to operate the connections and move the roller.

3. The combination with superposed beds, of means to draw webs over the beds respectively, a vertically reciprocating carriage above each bed, numbering mechanisms swung from the carriages, and means to alternately operate the web-drawing means and the carriages.

4. In a web attachment for platen printing presses, the combination with rollers to draw the web, of a train of gear wheels for said rollers; a wheel provided with spur teeth to drive the train and provided with bevel grooves at the sides of the spur teeth; back stop pawls engaging the grooves; detents engaging the teeth; means to intermittently operate said detents; mechanism to cut the web; and mechanism timed with the detent operating means to operate the web cutting mechanism.

5. In a double deck rotary web attachment the combination with a frame, of web drawing rollers mounted thereon, means to intermittently operate the rollers to deliver 5 webs therethrough, cutting mechanism to cut the webs, means to shift the webs forward or backward with relation to one another; said means comprising shafts rotatably mounted upon said frame, sprockets 10 fixed upon said shafts, chains around the sprockets, a crosshead fixed to the chains, and an adjusting roller carried by the cross head to raise or lower as the chains are operated by the sprockets, said rollers being 15 adapted to act on the web.
6. An apparatus of the class described comprising two platen presses, means to draw webs from the presses, superposed numbering devices between the presses and 20 the web-drawing means, means to operate the presses, means to intermittently operate the numbering devices, said presses and numbering devices operating to make imprints on the upper side of the web, and 25 means between the presses and the numbering devices to adjust the webs so as to regulate the position of the press and numbering imprints of one web relative to the press and numbering imprints of the other web.
- 30 7. An apparatus of the class described comprising superposed platen presses, means to draw webs along superposed paths, superposed numbering devices above said paths, means to operate the presses, means 35 to operate the numbering devices, and su-

perposed means to regulate relative lengths of the webs between the presses and the numbering devices.

8. In an apparatus of the class described 40 numbering mechanism comprising a cross-head having perforated end-plates, actuating rods through the end-plates, adjusting collars above and below the end-plates, depressing springs between the upper collars and the end-plates, blocks adjustably 45 clamped to the cross-head, numbering devices fastened to the blocks, and means to reciprocate the actuating rods.

9. In an apparatus of the character set forth, mechanism for resiliently holding the 50 web, said mechanism comprising a frame, an upper delivery pulling roller stationarily mounted on the frame, a lower delivery pulling roller adjacent the upper delivery pulling roller, an upper and a lower pulling 55 roller above and below the upper and lower delivery pulling rollers respectively, levers fulcrumed to the frame and journaling the lower delivery pulling roller and the upper and lower delivery pulling rollers respectively, 60 and springs to press the levers toward the upper and lower delivery pulling rollers respectively.

In testimony whereof, I have hereunto set my hand at Los Angeles, California, this 65 4th day of August, 1911.

CHARLES M. MEAD.

In presence of—

JAMES R. TOWNSEND,
L. BELLE RICE
